ASH TRAY

Irvin Pine, 820 University Blvd. E., Silver Spring, Md.

Filed Nov. 23, 1962, Ser. No. 72,581

Term of patent 14 years

(Cl. D85—2)

Fig. 1

Fig. 2

Fig. 3

Fig. 4

Fig. 5

Fig. 6

FIG. 1 is a side elevational view of an ash tray, showing my new design wherein the support members employ a donkey motif;

FIG. 2 is a top plan view with the cover removed;

FIG. 3 is a front elevational view with the cover in a raised position;

FIG. 4 is a side elevational view of a modification of my design wherein the support members employ a cat motif;

FIG. 5 is a top plan view of the modification with the cover removed; and

FIG. 6 is a front elevational view of the modification with the cover in a raised position.

I claim:

The ornamental design for an ash tray, as shown and described.
